US00D992528S

(12) **United States Design Patent** (10) **Patent No.:** **US D992,528 S**
Brunner et al. (45) **Date of Patent:** **** Jul. 18, 2023**

(54) **HEADSET**(71) Applicant: **Apple Inc.**, Cupertino, CA (US)(72) Inventors: **Robert D. Brunner**, Glen Ellen, CA (US); **Christopher Kuh**, San Francisco, CA (US)(73) Assignee: **Apple Inc.**, Cupertino, CA (US)(***) Term: **15 Years**(21) Appl. No.: **29/859,457**(22) Filed: **Nov. 10, 2022****Related U.S. Application Data**

(60) Continuation of application No. 29/823,119, filed on Jan. 14, 2022, now Pat. No. Des. 969,773, which is a continuation of application No. 29/795,780, filed on Jun. 21, 2021, now Pat. No. Des. 941,262, which is a continuation of application No. 29/706,360, filed on Sep. 19, 2019, now Pat. No. Des. 922,978, which is a continuation of application No. 29/642,633, filed on Mar. 30, 2018, now Pat. No. Des. 860,969, which is a continuation of application No. 29/574,209, filed on Aug. 12, 2016, now Pat. No. Des. 814,438, which is a continuation of application No. 29/504,827, filed on Oct. 9, 2014, now Pat. No. Des. 764,435, which is a continuation of application No. 29/464,539, filed on Aug. 18, 2013, now Pat. No. Des. 716,760, which is a division of application No. 29/426,082, filed on Jun. 29, 2012, now Pat. No. Des. 691,112, which is a continuation-in-part of application No. 29/410,585, filed on Jan. 9, 2012, now Pat. No. Des. 698,749.

Primary Examiner — Paula Allen Greene*(74) Attorney, Agent, or Firm* — Sterne, Kessler, Goldstein & Fox P.L.L.C.**CLAIM**

The ornamental design for a headset, as shown and described.

DESCRIPTION

FIG. 1 is a front perspective view of a headset showing the claimed design;

FIG. 2 is a rear view thereof;

FIG. 3 is a bottom view thereof;

FIG. 4 is a front view thereof;

FIG. 5 is a right side view thereof;

FIG. 6 is a left side view thereof; and,

FIG. 7 is a top view thereof.

The broken lines in the figures show portions of the headset that form no part of the claimed design.
